US00D761448S

(12) **United States Design Patent**
Parker

(10) **Patent No.:** **US D761,448 S**
(45) **Date of Patent:** **** Jul. 12, 2016**

(54) **TEMPLATE FOR TRAFFIC PATTERNS**

(71) Applicant: **Flint Trading, Inc.**, Thomasville, NC
(US)

(72) Inventor: **Andrew Jared Parker**, Jamestown, NC
(US)

(73) Assignee: **Flint Trading, Inc.**, Thomasville, NC
(US)

(**) Term: **14 Years**

(21) Appl. No.: **29/514,239**

(22) Filed: **Jan. 9, 2015**

(51) **LOC (10) Cl.** **25-01**

(52) **U.S. Cl.**
USPC **D25/153**; D10/64
